UNITED STATES PATENT OFFICE.

ARTHUR E. HAUCK, OF NEW YORK, N. Y.

KEROSENE-VAPOR BURNER.

1,324,115.

Specification of Letters Patent.

Patented Dec. 9, 1919.

Application filed September 19, 1918. Serial No. 254,731.

To all whom it may concern:

Be it known that I, ARTHUR E. HAUCK, a citizen of the United States, and a resident of the city of New York, county of Kings and State of New York (whose post-office address is 101 Eleventh street, Brooklyn, N. Y.), have invented a new and useful Improvement in Kerosene-Vapor Burners, of which the following is a specification.

10 The object of my invention is to provide a burner of this class in which a flame can be projected with a predetermined intensity against the vaporizing part of the apparatus which intensity may be regulated 15 at pleasure while the burner is in operation so that under all conditions of service the heat of the burner is under complete control and the flame may be always proper so that the apparatus is not injured by over- 20 heating and a deposit of carbon is prevented on the walls of the passages of the apparatus through which vapor passes before being brought to the point of combustion. This and other objects are accomplished by my 25 invention, one embodiment of which is hereinafter more particularly set forth.

For a more detailed description of my invention, reference is to be had to the accompanying drawing, forming a part here- 30 of, in which—

Figure 1 is a longitudinal section of my improved burner, the section being taken on the line 1—1 of Fig. 2 looking in the direction of the arrows.

35 Fig. 2 is a horizontal section taken through the upper portion of Fig. 1 as indicated by the line 2—2, looking in the direction of the arrows.

Fig. 3 is a sectional view taken on the line 40 3—3 of Fig. 2, looking in the direction of the arrows.

Fig. 4 is a plan view which shows the openings through which the flames protrude and the gauze for preventing a flash back.

45 Throughout the various views of the drawings, similar reference characters designate similar parts.

My improved vaporizer burner 1 has a top casting 2 which contains the necessary 50 passages and a regulator 3, which will be described below, a downwardly extending pipe 4 which has a U 5 which carries an ignition pan 6 at its lower end, and this U 5 is also provided with a check 7 above which 55 is a Bunsen burner 8 which is mounted on the vertical pipe 4.

More particularly, the vaporizer casting 2, which is called the casting although it may be made in any suitable way, has two parallel passages 9 and 10 and a cross connecting passage 11 all of which are suitably bored or reamed. An access may be had to them by removing the screws 12, as is obvious. Vapor or kerosene passes into the apparatus through the single end of the 60 passage 9 and thence to the passage 11 and from there to the passage 12, and thence down the pipe 4 through the U 5 to the check 7. A screw 12 in the U 5 permits access to the interior of this U so that its 65 passage may be made and kept in proper condition at all times. Over the burner 8 the casting 2 is somewhat enlarged, as shown at 13, so as to give a large surface for the action of the heating flames. This enlargement may be dispensed with if desired.

This casting 2 is provided with a rod 14 which is fixed in one end and substantially about the axis of the casting and the regulator 3 slides on this rod and on the casting, 80 as shown. This regulator is composed of an inner shell 15 which is preferably made of cast iron or similar material and over this is placed asbestos 16 or similar non-conducting material which may stand the flame indefinitely without injury. A small handle 17 is provided by means of which this regulator may be moved more or less on and off the casting so that more or less of the part having vapor passages is exposed to the 85 action of the flame. This permits the apparatus to be used for outdoor work or other work where an even or regulated heating effect is required.

The pan 6 is secured to the U 5 by means 90 of a suitable cap screw 18 fixed in the bottom of the U 5, as indicated. This pan is used whenever the apparatus is started by placing therein a small amount of oil or kerosene or gasoline or other substance and 100 igniting the same so as to heat the U 5 and vaporized oil passing therethrough so that this vapor will issue through the check 7 with some force. This vapor then passes into the Bunsen tube 8 which has suitable inwardly extending lugs 19 at its upper end which carry a gauze 20 which in turn supports a collar which depends from the perforated metal plate 21. The vapor which issues from the check 7 mingles with air in 110 the Bunsen tube 8 and is ignited above the plate 21 so that a hot set of flames issue

through the perforations in this plate 21 and these flames heat the enlarged part of the casting 2 and the passages therein contained as well as adjacent parts of this casting so that the fuel passing through this passage is vaporized and heated and as it is under pressure it issues from the check 7 with increased force. By shifting the regulator 3 on the casting 2, as above described, it is possible to regulate this force and thereby regulate the intensity of combustion so that flames of the desired intensity and color always issue from the apparatus and the passages in the casting 2 are not overheated so as to cause a deposit of carbon therein which will choke said passages.

The points of application of the flames thereon from the perforated diaphragm 21 may always be regulated to some extent by raising or lowering the Bunsen burner 8 which is done by manipulating a set screw 22 in a perforated ear 23 which is preferably made integral with this burner 8. The perforation in this ear has a sliding fit with the exterior of the pipe 4 and the set screw 22 is used to fix the ear in any desired position on this tube. Obviously, by raising or lowering this tube it is possible to regulate the distance between the perforated plate 21 and the lower surface of the casting 2 and thereby, to some extent, regulate the heating effect.

The use of the metal plate 21 over the screen 20 serves an additional purpose in

that it protects this screen because the greater part of combustion takes place out of the perforated plate 21 and not immediately against the screen 20. The plate 21 is large enough to easily withstand, without injury, the temperature incidental to its use and because of the protection it gives, the same is true of the gauze 20 which otherwise would be short lived.

In view of the foregoing, it is obvious that when my improved burner is used, it can be used with any suitable hydrocarbon or other fuel and the regulator 3 may be placed so that the desired amount of the casting 2 is exposed to the heating flame and all tendency to overheat or prematurely cool is overcome and this is true even though the apparatus be used in a draft or under other adverse conditions either in or out of doors.

Having thus described my invention, what I claim is:

In a device of the class described, a casting with parallel passages extending entirely across the device and a vertically disposed tube connected to one of said passages, a bent part with a check secured to said vertically disposed tube, a Bunsen burner mounted on said vertically disposed tube and above the level of said check, a gauze mounted in said burner and above said check and a perforated plate mounted above said gauze.

Signed at the city, county and State of New York, this 18th day of September, 1918.

ARTHUR E. HAUCK.
